(57) **CLAIM**

The ornamental design for a tubing clip as shown and described.

DESCRIPTION

FIG. 1 is an isometric view of the tubing clip of the present invention.

FIG. 2 is a front view of the tubing clip of the present invention.

FIG. 3 is a rear view of the tubing clip of the present invention.

FIG. 4 is a right-side view of the tubing clip of the present invention.

FIG. 5 is a left-side view of the tubing clip of the present invention.

FIG. 6 is a top side view of the tubing clip of the present invention; and,

FIG. 7 is a bottom side view of the tubing clip of the present invention.

The broken lines in the drawings indicate portions of the tubing clip that form no part of the claimed design.

1 Claim, 4 Drawing Sheets
